UNITED STATES PATENT OFFICE.

RAYMOND F. STRIEF AND WILLIS H. STRIEF, OF CINCINNATI, OHIO.

WINDOW SEAT.

Application filed August 24, 1921. Serial No. 495,052.

To all whom it may concern:

Be it known that we, RAYMOND F. STRIEF and WILLIS H. STRIEF, citizens of the United States, residing at Cincinnati, in the county 5 of Hamilton and State of Ohio, have invented certain new and useful Improvements in Window Seats, of which the following is a specification.

Our invention relates to window seats, 10 intended for use of a person washing the outside of windows, for permitting the user to sit conveniently without undue strain while washing the outside of the windows.

It is the object of our invention to provide 15 a novel window seat of the character mentioned, arranged to be selectively attached to the windows of a building, for instance, a residence; and to provide novel means whereby the same may be adjusted for windows 20 of different dimensions.

The invention will be further readily understood from the following description and claims, and from the drawings, in which latter:

Fig. 1 represents a plan view of our improved device.

Fig. 2 is a bottom view of the same.

Fig. 3 is a rear end elevation of the same.

Fig. 4 is a side elevation of the same, showing the same in position of use on a window sill, the latter being shown in cross-section.

Fig. 5 is a cross-section, taken on the line 5—5 of Fig. 1, showing the rear support of the window seat in position of use in full 35 lines, and in retracted relation in dotted lines.

Fig. 6 is a cross-section, taken on the line 6—6 of Fig. 1.

Fig. 7 is an enlarged bottom view, showing a detail of the adjustable securing means for the hook-strap.

Fig. 8 is a vertical cross-section of the same, taken on the line 8—8 of Fig. 7; and,

Fig. 9 is a vertical cross-section of the same, taken in the plane of the line 9—9 of Fig. 8.

The window seat comprises a seat-body 11, which may be of wood. Straps 12 are secured to the seat-body and extend forwardly thereof. Each of the straps is at its forward end provided with a hook 15. The straps are preferably strips of iron or steel. They are preferably adjustable on the seat-body, for instance, by means of screws 16, 55 which pass through holes 17 of the straps and slots 18 in the seat-body. The lower

face of the seat-body is provided with elongated recesses 21, forming enlargements of the slots, and forming shoulders 22 in the recesses at the lower ends of the slots. 60 Washers 23 are received over the screws against the shoulders, nuts 24 being received over the threaded ends of the screws, for clamping the straps, screws, seat-body, washers and nuts together. The washers 65 and nuts are countersunk in the elongated recesses 21.

The window opening is shown at 27, at the lower end of which there is a usual window sill 28. The window sill comprises the 70 usual inner finishing board 29, which overhangs the inner edge of the window frame, as shown at 30. The hooks are arranged to be received over this inner overhanging edge. 75

The hooks are received about the inner face of the overhanging inner portion, the ends of the hooks being received under the same for resisting upward movement of the hooks. This inner finishing board is received between the hooks and the inner edge 80 31 of the seat-body, the adjustment of the straps on the seat-body being such, that said inner finishing board substantially fills the space between said hooks and inner edge 85 31.

The seat is readily hooked in place by raising its outer end, so as to place the lower edges of the hooks under the inner edge of the window sill, the seat being lowered to 90 move the front end 31 of the seat-body, to outside of said inner finishing board, with said straps substantially on a level with and resting on the upper surface of said inner finishing board. 95

Means are provided for supporting the seat-body in a substantially horizontal position, for which purpose I provide a pivoted support 36, which is of greater height than width, when in active or supporting relation, and is arranged to be placed lengthwise of the seat-body when in retracted or inactive relation, as shown in Fig. 5. This support is shown in the form of a yoke, formed up out of a bent strip of metal, comprising flanges 37 connected by a cross-strip 38. Each of the flanges is provided with a hole 39, one corner of the end of each flange being relieved, as shown at 40, for permitting pivoting of the flange close to the bottom face of the seat-body, while permitting the yoke to swing so as to be placed substan- 105 110

tially parallel with the seat-body. The other corner 41 of the end of the flange is arranged to impinge the lower face of the seat-body so as to limit the swinging movement 5 of the yoke and act as a stop for positioning the yoke in up and down relation under the seat.

At each side of the seat-body there is a depending flange 44, which is provided with 10 a series of holes 45, the series of holes and the flanges extending lengthwise with relation to the straps. A pivot-rod 46 is received through the holes 39 in the flanges 37 and through a pair of complementary holes in 15 the series of holes 45 at the respective sides of the seat-body, so as to locate the supporting yoke adjustably forward or back with relation to the seat-body and an outer portion 47 of the window-sill, on which said 20 yoke rests for supporting the rear of the seat. A nut 48 is received over the threaded end of the pivot-rod for holding the same in place.

The outer portion 47 is, in practice, lower 25 than the inner finishing board 29 of the window sill, over which the inner ends of the straps are placed. The flanges 44 are shown as one of the wings of angle irons, the other wings 49 of said angle irons being 30 secured to the bottom face of the seat-body by means of screws 50.

Our invention provides an economical, ready and very serviceable window seat, employable in various relations, and adjustable 35 for accommodating window sills of different shapes and dimensions. It provides a ready means, very readily transferable from one window sill to another, so arranged that the user may sit comfortably, 40 with the rear portion of the seat on a level with the front portion, to avoid undue strains and prevent exhaustion and pain.

Having thus fully described our invention, what we claim as new, and desire to 45 secure by Letters Patent, is:

1. In a window seat, the combination of 50 a seat-body, a strap at each side of said seat-body, each of said straps provided with a downwardly projecting hook arranged to engage an inwardly extending projection of a window-sill, means for adjusting said straps lengthwise of the said seat-body, a pair of flanges secured to said seat-body and extending below said seat-body, said flanges

provided with a series of holes arranged 55 longitudinally thereof, supporting parts extending downwardly when in supporting relation, said supporting parts provided with apertures and with stops impinging said seat-body above said apertures, said 60 stops arranged to automatically impinge the bottom of said seat-body upon downward swinging movement of said supporting parts and arranged to automatically limit movement of said supporting parts past 65 a point of supporting relation to said seat, and pivot means received through said holes and apertures at selective positions lengthwise of said flanges for selectively positioning said supporting parts under said seat-body toward and from said hooks, and said supporting parts remaining free to be swung on said pivot-means into positions under said seat-body extending lengthwise of said flanges. 75

2. In a window seat, the combination of a seat-body, a strap at each side of said seat-body, each of said straps provided with a downwardly projecting hook arranged to engage an inwardly extending projection of a window-sill, means for adjusting said straps lengthwise on said seat-body, a pair of flanges secured to said seat-body and extending below said seat-body, each of said flanges provided with a series of holes, a 80 supporting yoke having pivot-flanges extending upwardly when said yoke is in supporting relation, said pivot-flanges provided with holes and a stop arranged to limit movement of said pivot-flanges past a point 85 of supporting relation of said yoke, and a pivot-rod received through said holes in said pivot-flanges and selective complementary holes of said series of holes in said 90 respective first-named flanges, for selectively positioning said supporting yoke under said seat-body, and said supporting yoke arranged to be swung on said pivot-rod into a position under said seat-body extending lengthwise between said flanges. 95

In testimony whereof, we have hereunto signed our names in the presence of two subscribing witnesses.

RAYMOND F. STRIEF.
WILLIS H. STRIEF.
